(57) **CLAIM**

The ornamental design for a display panel with an animated graphical user interface for flight information, as shown and described.

DESCRIPTION

The file of this patent contains at least one drawing/photograph executed in color. Color copies of this patent with color drawing(s)/photograph(s) will be provided by the Office upon request and payment of the necessary fee.

FIG. 1 is a front view of a first image of a display panel with an animated graphical user interface for flight information of a first embodiment of the present invention;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh view thereof;

FIG. 12 is a front view of a first image of a second embodiment thereof;

FIG. 13 is a front view of a second image thereof;

FIG. 14 is a front view of a third image thereof;

FIG. 15 is a front view of a fourth image thereof;

FIG. 16 is a front view of a fifth image thereof;

FIG. 17 is a front view of a sixth image thereof;

FIG. 18 is a front view of a seventh image thereof;

FIG. 19 is a front view of an eighth image thereof;

FIG. 20 is a front view of a ninth image thereof;

FIG. 21 is a front view of a tenth image thereof;

FIG. 22 is a front view of an eleventh image thereof;

FIG. 23 is a front view of a first image of a third embodiment thereof;

FIG. 24 is a front view of a second image thereof;

FIG. 25 is a front view of a third image thereof;

FIG. 26 is a front view of a fourth image thereof;

FIG. 27 is a front view of a fifth image thereof;

FIG. 28 is a front view of a sixth image thereof;

FIG. 29 is a front view of a seventh image thereof;

FIG. 30 is a front view of an eighth image thereof;

FIG. 31 is a front view of a ninth image thereof;

FIG. 32 is a front view of a tenth image thereof; and,

FIG. 33 is a front view of an eleventh image thereof.

(Continued)

The outermost rectangle in broken lines in each of the drawings illustrates the display panel. The broken lines in each of the figures illustrating the display panel, and the broken lines illustrating alphanumeric characters, symbols and icons that are portions of the graphical user interface form no part of the claimed invention.

The appearance of the animated image transitions sequentially between the images shown in FIGS. 1-11, in FIGS. 12-22, and in FIGS. 23-33. The process or period in which one image transitions to another forms no part of the claimed design.
